Inventor.

Andrew Hartup

United States Patent Office.

ANDREW HARTUPEE, OF PITTSBURG, PENNSYLVANIA.

Letters Patent No. 61,735, dated February 5, 1867; antedated January 20, 1867,

IMPROVEMENT IN STEAM-ENGINE AIR-PUMPS.

The Schedule referred to in these Letters Patent and making part of the same.

TO ALL WHOM IT MAY CONCERN:

Be it known that I, ANDREW HARTUPEE, of the city of Pittsburg, in the county of Allegheny, and State of Pennsylvania, have invented an improved Device for Working the Air-Pumps of Steam Engines; and I do declare that the following is a full, clear, and exact description of the same, reference being had to the accompanying drawings, making part of this specification, in which my improvement is represented in longitudinal section.

My invention consists in a combination of levers and pitman with the sliding-head, piston-rod, and slides of a horizontal or inclined steam engine, by which I obtain two full strokes of the air-pump or air-pumps for one stroke of the piston of the steam engine, whereby I am able to make the air-pump much smaller than it should be were it to make but one stroke for every stroke of the steam engine.

A is the framework of the engine, on which the cylinder B is fastened; C is the pillar-block; D, the crank; E, the pitman; G G are the slides; H is the piston; I, the piston-rod; K, the sliding-head; L, the pump rock-beam; M, the supports for the beam L; O O', the air-pumps; P, the condenser; R R', the pump-pistons; r r', the pump-rods, and S is the link, which is jointed to the head K and to the lever L, to give motion to that lever, as hereafter described. When the piston is in, the head K is at the point U, and the link S is in the position of the red line U V; when the piston is mid-cylinder, (as represented in the drawings,) the link S is in the position from T to Z; and when the piston is out, the head K is at the point W, and the link S is in the position indicated by the red line W V, thus making two strokes of the pumps O O' for one stroke of the piston H.

What I claim as my invention, is—

In horizontal or inclined steam engines, the combination of the link S and lever L with the head K, piston-rod I, and slides G G, arranged as described and for the purpose specified.

ANDREW HARTUPEE. [L. S.]
